UNITED STATES PATENT OFFICE.

CYRUS S. HOOD, OF CORNING, NEW YORK.

RADIATOR FOR HOT-AIR FURNACES.

SPECIFICATION forming part of Letters Patent No. 293,025, dated February 5, 1884.

Application filed September 25, 1883. (No model.)

To all whom it may concern:

Be it known that I, CYRUS S. HOOD, a citizen of the United States, residing at Corning, in the county of Steuben and State of New York, have invented new and useful Improvements in Radiators for Hot-Air Furnaces and Heating-Stoves, of which the following is a specification.

The object of my invention is to produce a radiator for hot-air furnaces and stoves adapted to distribute the waste products of combustion in separate thin volumes, to obtain a large extent of radiating-surfaces in direct contact with the air to be heated, entering the heating-spaces in thin volumes, and to obtain a direct draft from the combustion-chamber when the pressure of the gas is sufficient to open the valves automatically. The radiator is mounted upon the fire-pot, and is constructed with one, two, or more circular flues surrounding the combustion-chamber, each having direct communication with the fire-pot at substantially the same point, each flue having substantially the same exit, each flue divided by a horizontal partition, and each flue giving out its heat in direct contact with the air to be heated. A damper is arranged horizontally in a vertical central chamber, and divides it to form the upper part of the combustion-chamber and a top exit-chamber, and the handle of this damper is so arranged in relation to the furnace-door that the opening of the latter will open the damper and the closing of the door will allow the damper to close of itself, thus allowing the gas and smoke to pass off through the valved opening directly into the top exit-chamber when the furnace-door is open. The products of combustion enter the circular flues from the combustion-chamber, and, passing around beneath the horizontal partition-plate to a point diametrically opposite, return above the partition-plate and pass into the exit-chamber at a point just above that at which they entered the said circular flues, distributing the heat evenly through the walls to the air which enters at the base of the furnace, and, passing over the outer walls of the fire-pot, passes up through the narrow flues formed by the heating-walls into the inclosing-case, whence it passes through the conducting-pipes to the apartments to be heated.

Referring to the accompanying drawings,

Figure 1 represents a vertical section of a hot-air furnace embracing my invention; Fig. 2, a horizontal section taken on the line $x x$ through the lower flues of the radiator; Fig. 3, a similar section taken on the line $y y$ through the upper or return flues of the radiator; Fig. 4, a vertical cross-section of the radiator on the line 2 2 of Fig. 2; and Fig. 5, 60 a view of the radiator, showing the relation of its damper-handle to the feed-door.

My radiator is adapted for use with furnaces, heating-drums, and stoves, and is designed to take advantage of the heat of any given quantity of fuel. The radiator is inclosed by a cylindrical jacket, A, which also incloses the fire-pot and ash-pit, and confines and supplies the heated air to the conducting-pipes.

The radiator consists of one, two, or more concentric flues, of a suitable depth and width, separated by an intervening space, E, and it has a vertical central chamber, F, directly above and opening into the fire-pot. Horizontal partitions G divide the concentric flues, and a horizontal damper, H, divides the vertical central chamber, F, to the top of which the smoke-pipe connects. The inner concentric flue, B, opens into the combustion-chamber 75 below the bottom of the radiator by the openings $a a$ in the bottom plate of the radiator, which, by means of short pipes or collars $b b$, connect with openings $a' a'$ in a dome, I, upon which the radiator is directly mounted, the 80 said dome being mounted upon the fire-pot and forming the combustion-chamber. The outer concentric flue, C, opens into the vertical central chamber, F, by a wall-opening, c, therein beneath the damper, which opening c also 85 communicates with the open ends c' of the inner flue, B. The vertical walls $d d$, crossing the intervening cold-air spaces, E, form a cross-flue, J, which opens direct into the combustion-chamber and into the concentric flues, so 90 that both concentric flues open into the combustion-chamber at substantially the same point below the horizontal partition at the back of the radiator, as shown in Fig. 2. The horizontal partition G of the inner concentric 95 flue, B, is open at K at a point diametrically opposite the wall-opening c , and at this point K the inner concentric flue, B, below the partition G, opens into the concentric flue B' 100.

above said partition, which upper flue, B', opens into a vertical central chamber, F', by a wall-opening, e, and the cross-flue J' at a point above the damper directly over the 5 lower back wall-opening, e, of the central flue. The horizontal partition G of the outer concentric flue, C, is open at L at the front of the radiator, and at this point L the outer concentric flue, C, below the partition G opens into 10 the concentric flue C' above said partition, which upper flue, C', opens into the vertical chamber F' by the wall-opening e. The vertical walls d d, which cross the intervening cold-air spaces, E, form a cross-flue, J', which opens 15 direct into the top exit-chamber and into the concentric flues, so that both concentric flues open into the central top exit-chamber at substantially the same point above the damper of the central flue. By this construction the products of combustion pass from the combustion-chamber into the lower cross-flue, J, and, entering the concentric flues which open therein, pass 20 around both sides of the radiator to the front thereof, and, rising through the opening K, pass 25 back to the same point above the partitions G into the top cross-flue, J', and into the top central chamber, F', which has a top central opening, over which the smoke-pipe connects. As 30 the radiator is inclosed by the outer casing or jacket, leaving a space all around the radiator, the cold air entering at the bottom of the jacket rises in the spaces between the concentric flues, and is heated by impinging against the hot surfaces of said flues, over the inner 35 walls of which the heat is caused to pass back and forth on both sides of the center of the radiator, and thus all the heat is utilized in raising the temperature of the air passing up through the heating-spaces. The arrangement 40 of the horizontal partitions in the concentric flues and the damper in the vertical central chamber practically divides the radiator horizontally, and the damper gives the advantage of a direct vertical draft from the combustion-chamber, and thus allows the use of soft coal, 45 which is an important matter in a heating-furnace. The damper is weighted on one side at H', and is thereby made self-closing, while its handle M passes through the radiator just 50 above the feed-door N, and is bent or curved downward in front thereof in such manner that the opening of the feed-door will bring its upper edge against the depending curved handle, and raising it thereby open the damper. 55 As the damper-handle is not attached to the door, the damper can be opened and held open when desired without opening the door.

Instead of weighting the damper, the curved or bent handle thereof may be weighted.

60 Referring to the draft of the furnace, I propose to make the flues sufficiently large to give the required indirect draft for burning soft coal, while in case of an overcharge of gas in the combustion-chamber the pressure caused 65 thereby will lift and open the damper by reason of its being pivoted to one side of the center, and thus give a direct draft to relieve

such pressure, the damper closing as soon as the undue pressure is relieved.

The cold-air induction-pipe may be connect- 70 ed with the casing at any suitable point.

The state of the art shows that much has been done in heating-drums for stoves and in radiators for hot-air furnaces in which concentric fire-flues receive and discharge the 75 products of combustion, and give out their heat in intervening open spaces for heating air passing through said spaces in contact with the walls of said fire-flues; and my invention does not broadly comprehend such a thing, 80 but only the matters of improvement to which the claims are specially directed, and which consists, essentially, in using one or more concentric flues, each divided into an upper and a lower communicating passage by a horizontal 85 partition, combined with smoke-chambers and a damper for effecting their division and direct communication, in the way and for the purpose stated.

I claim—

1. The radiator or heater embracing two or more concentric fire-flues divided horizontally, the vertical central chamber, a damper for dividing said chamber, a cross-flue opening into the lower part of said chamber, communicating with the lower concentric fire-flues at the rear side of said heater, a cross-flue opening into the upper exit part of said central chamber, communicating with the upper concentric fire-flues, and open air-spaces between the said concentric fire-flues, substantially as described, for the purpose set forth. 90

2. A heating-drum or radiator having a central rising chamber, F, two or more concentric flues, each divided into an upper and a lower communicating passage by a horizontal partition, a top exit-chamber, F', and a damper dividing said central rising chamber from the exit-chamber, such division being coincident with the horizontal division of the concentric 105 flues, for the purpose stated.

3. The combination, with a heater composed of concentric fire-flues, intervening open air-spaces, and a vertical central chamber communicating with the combustion-chamber and with the said fire-flues, substantially as described, of a self-closing damper arranged to divide said vertical flue, having an outside bent or curved handle, and the feed-door in the casing of the outer concentric flue, arranged to press against and turn said handle to open the damper in opening said door, substantially as herein set forth. 115

4. The combination, with the fire-pot and the dome, of a heater composed of concentric 125 fire-flues divided horizontally, and a vertical central chamber divided by a damper, and open air-spaces between the said fire-flues, the pipes or collars b b, connecting the inner of said fire-flues with the combustion-chamber, 130 the lower cross-flue connecting the outer of said fire-flues with the lower part of the central chamber and with the combustion-chamber, and the upper cross-flue connecting the

said fire-flues with the upper part of said central chamber, substantially as herein set forth.

5. The combination, with the rising chamber F, of one or more separate concentric fire-flues divided horizontally into separate lower and upper communicating flues, the lower and upper cross-flues, J J', the central top exit-chamber, F', the damper H, and one or more open concentric air-heating spaces, the said 10 concentric fire-flues opening into the said cross-flues and into the said central rising and exit chambers at points directly over each other, substantially as described.

6. The combination, in a radiator, of the 15 central rising and exit chambers, F F', one or more separate concentric fire-flues divided horizontally, and communicating by openings in said divisions, the cross-flues J J', communicating with said separate concentric flues 20 and the said central chambers, and the open air-heating spaces, with a damper dividing the said central chambers, adapted to be opened by the pressure of the gas in the combustion-chamber, and to close automatically 25 upon the relief of said pressure, substantially as described.

7. An air-heater for stoves and furnaces, having one or more separate concentric fire-flues divided horizontally, a central rising and exit chamber, a damper dividing said central 30 chamber in line horizontally with the fire-flue divisions, and one or more open air-heating spaces between the said fire-flues, the latter receiving the products of combustion through an opening in said central rising chamber beneath its dividing-damper and discharging them through an opening in said central exit-chamber above said damper, both the receiving and discharging openings being on the same side of said central chamber, and communicating with the said fire-flues by openings in their division-plates, substantially as 35 described.

In testimony whereof I have hereunto set my hand in the presence of two subscribing 40 witnesses.

CYRUS S. HOOD.
